Attorney

UNITED STATES PATENT OFFICE.

JOHN KOPEC, OF ELIZABETH, NEW JERSEY.

LIFE-SAVING SUIT.

1,262,358.

Specification of Letters Patent.

Patented Apr. 9, 1918.

Application filed November 22, 1917. Serial No. 203,856.

To all whom it may concern:

Be it known that I, JOHN KOPEC, a subject of the Emperor of Austria, residing at Elizabeth, in the county of Union and 5 State of New Jersey, have invented certain new and useful Improvements in Life-Saving Suits, of which the following is a specification.

This invention relates to certain new and 10 useful improvements in life saving suits.

The primary object of the present invention is the provision of a life saving device in the nature of a life preserver that is easy and inexpensive to manufacture, and 15 may be readily worn without discomfort to the person, the device being easily put on and taken off when desired.

A further object of the device is the provision of a floating member adapted for 20 positioning portions thereof in contact with the body of the wearer and arranged for accommodating the movements of the body.

With these general objects in view and others that will appear as the nature of the 25 invention is better understood, the same consists in the combination and construction of parts hereinafter more fully described, illustrated in the accompanying drawings, and then claimed.

30 In the drawings forming a part of this application, and in which like designating characters refer to corresponding parts throughout the several views,

Figure 1 is a front view of the device 35 operatively arranged upon a person,

Fig. 2 is a longitudinal sectional view thereof detached,

Fig. 3 is an interior elevational view of the device and

40 Fig. 4 is a sectional detail view of the forward securing portions thereof.

A person 10 is illustrated in Fig. 1 having the device 11 secured in position by shoulder straps 12 and leg attaching 45 straps 13.

A plurality of pneumatic tubes 14 are arranged having a binding or strip 15 connecting them together at one end while a similar strip 16 is attached between their opposite ends arranging the tubes 14 in parallel relation. Hold-fast devices such as buttons 17 are carried by the binding 15 while button holes 18 are arranged through the strip 16 for receiving the said buttons when 55 the device is arranged encircling the trunk portion of the body. Each tube 14 may be

individually inflated to the desired degree through a check valve 19 arranged for each tube adjacent the binding strip 15. The shoulder straps 12 are carried by the uppermost tube 14 and are each provided with a buckle 20. The leg straps 13 are attached to the lowermost tube and consist of depending straps 21 each having an encircling strap or band 22 connected therewith by means of an adjustable buckle 23.

An apron or protecting covering 24 is secured to the rear sides of the tubes 14 connecting the same together and is adapted to overlie the tubes and also may be turned inwardly forming a lining therefor while the shoulder straps 12 at the rear of the device may overlie the covering 24. The covering 24 need however be only attached to the upper tube 14 and will then be free for wrapping around the adjacent tubes inwardly thereof as desired, it being understood that the tubes are connected together by the bindings 15 and 16 heretofore referred to. The device may be readily positioned upon the body for wearing as will be evident and may be easily removed by releasing the button 17 from the button holes 18. The resiliency of the tubes 14 which are preferably formed of rubber together with their separated arrangement permit them to conform to the shape of the body so that the same may be comfortably worn when desired.

While I have shown and described the 90 preferred embodiment of my invention, it will be understood that minor changes may be made therein without departing from the spirit and scope of the invention as claimed.

What I claim as new is:—

1. A device of the class described comprising a plurality of pneumatic tubes, connectors between the opposite ends of the said tubes, securing means carried by said connectors, a wrapping member carried by 100 one of the tubes and body attaching straps carried by the upper and lower tubes.

2. A device of the class described comprising a plurality of inflatable tubes of equal length, a binding attached to the opposite ends of the tubes with the latter positioned in parallelism, detachable connections between the said binding, a covering apron for the tubes attached to a terminal one of the tubes and adapted for overlying 110 the adjacently positioned tubes when the device is operatively arranged, and means

carried by the tubes adapted for attaching the device to the body.

3. A device of the class described comprising a plurality of inflatable tubes of equal length, a binding attached to the opposite ends of the tubes with the latter positioned in parallelism, detachable connections between the said binding, a covering apron for the tubes attached to a terminal one of the tubes and adapted for overlying the ad-

jacently positioned tubes when the device is operatively arranged, shoulder straps carried by the upper tube, depending straps carried by the lower tube, encircling leg straps adjustably attached to the depending straps, and a check valve provided for each tube. 15

In testimony whereof I affix my signature.

JOHN KOPEC.
